C. H. LAND, JR

PENCIL SHARPENER

Filed March 20, 1922

Inventor

Charles H. Land, Jr.

By

J. S. Thomas

Attorney

UNITED STATES PATENT OFFICE.

CHARLES H. LAND, JR., OF DETROIT, MICHIGAN, ASSIGNOR OF ONE-HALF TO RUDOLF E. ESCH, OF DETROIT, MICHIGAN.

PENCIL SHARPENER.

Application filed March 20, 1922. Serial No. 545,068.

To all whom it may concern:

Be it known that I, CHARLES H. LAND, Jr., citizen of the United States, residing at Detroit, county of Wayne, State of Michigan, have invented a certain new and useful improvement in Pencil Sharpeners, and declare the following to be a full, clear, and exact description of the same, such as will enable others skilled in the art to which it pertains to make and use the same, reference being had to the accompanying drawings, which form a part of this specification.

My invention relates to pencil sharpeners shown in the accompanying drawings and more particularly pointed out in the following specification and claims.

In draughting rooms or other offices where drawing pencils are extensively used the proper sharpening of the pencil point—either rounded or chiseled—is a very important factor in the preparation of accurate drawings, it being essential that the pencil points should be very sharp and properly formed to produce drawings of a high standard of execution.

The usual practice is to sharpen the leads by means of a flat file or upon a sheet of abrasive paper or cloth mounted upon a short stick. This however is objectionable due to the formation and scattering of the dust, necessitating the sharpener being placed in an inconvenient location that the drawing may not be soiled.

Such a device for sharpening pencils is also objectionable due to the formation of irregular points resulting from the pencil being held at variable angles.

It is therefore the object of the present invention to eliminate these objectionable features.

The primary object of the invention is to produce a sharpening device by which pencil leads may be rapidly and accurately shaped without danger of breaking their delicate working edges.

A further object is to produce a sharpening device in which the dust produced by sharpening the lead is retained within its enclosing walls;—it may therefore be used directly upon the drafting board.

A further object of the invention is to provide a device in which the abrading or cutting surfaces may be easily and quickly renewed when required.

With the foregoing and other objects in

view which will appear as the description proceeds the invention further resides in the combination and arrangement of parts and in the details of construction hereinafter described and claimed, it being understood that changes may be made in the precise embodiment of the invention herein disclosed without departing from the spirit of the same.

In the drawings accompanying this specification:

Figure 1 is a perspective view of the device with the cover in place.

Figure 2 is a perspective view of the device with the cover removed showing its interior construction.

Figure 3 is a vertical cross-sectional view showing a pencil in position for sharpening the lead.

Figure 4 is a perspective view of the device showing the elastic band and abrasive strip divided, in order that both ends may flare to receive a pencil, with one end of each strip overlapping the adjacent end of the opposing strip.

Referring now to the letters of reference placed upon the drawings:

A, denotes a rectangular shaped box fitted with a removable cover B having a slot B' through which a pencil may be inserted for sharpening. Secured to the bottom of the box are two opposing walls C, C, having flaring ends, constructed of thin resilient sheet metal forming in cross-section a V-shaped channel between the walls;—one of the walls being relatively longer than the other. Lodged between the walls C, C, is a looped rubber band D with flaring ends conforming to the ends of the walls C, C, with one end of the band projecting beyond its other end. E, denotes a strip of abrasive paper or cloth looped at E' to conform to the contour and length of the rubber band.

In using this device the wood is removed from one end of the pencil to expose the required length of lead. The pencil is inserted between the opposing abrasive surfaces by way of the open loop E' or between the flaring ends E² at the opposite end of the box. The pencil is held in such a position that the lead only comes between the opposing faces of the abrasive material. If a chisel point is desired the pencil is reciprocated back and forth until the lead is given the desired edge. If however a tapering point is required the pencil is rotated

as it is reciprocated back and forth until the desired cone-shaped point is obtained.

The walls being constructed of resilient material act as a spring to maintain opposing walls of the rubber band in proper relation, while the latter being of soft material acts as a cushion;—thus a point of any desired degree of fineness may be obtained by varying the depth of the pencil in motion,—the rubber cushion overcoming any irregularities due to the reciprocating movement of the pencil. The flare given to the abrasive strip at one end and the “open loop” at the opposite end of the box offers ready admission for the lead,—while the extended end of the abrasive strip at the flaring end permits sharpening of the lead in spring bow pencils or compasses.

In Figure 4 both the band and the abrasive strip is shown divided and flaring at each end of the box for the ready admission of a pencil,—the rubber strip and the abrasive element at one end of the box overlapping the adjacent end of the opposing rubber strip and abrasive element, whereby the lead of a spring-box pencil or the like may be readily sharpened.

Having thus described my invention what I claim is:

- 30 1. In a device of the character described, a box-like structure; opposing elastic rubber surfaces extending longitudinally within the box-like structure, having overlapping flaring ends; flexible opposing abrasive surfaces lodged between the rubber surfaces having overlapping flaring ends conforming to the flaring ends of the rubber surfaces and means for yieldingly supporting said rubber and abrasive surfaces within the box.
- 40 2. In a device of the character described, a box-like structure, a divided yieldable surface extending longitudinally between the walls of the box-like structure and a divided abrasive element lodged between the divided yieldable surfaces.
- 45 3. In a device of the character described,

a box-like structure including a removable slotted cover, a pair of opposing yieldable surfaces extending longitudinally within the box and a pair of opposing abrasive strips lodged between the opposing yieldable surfaces.

4. In a device of the character described, a box-like structure including a removable slotted cover, a pair of walls formed of resilient sheet metal spaced apart and extending longitudinally within the box, a pair of opposing strips of rubber lodged between said resilient walls and opposing abrasive surfaces, and a pair of opposing abrasive strips lodged between the opposing strips of rubber.

5. In a device of the character described, a box-like structure including a removable slotted cover, a pair of rubber bands extending longitudinally within the box, and a pair of abrasive strips lodged between the opposing surfaces of the rubber bands.

6. In a device of the character described, a box-like structure including a removable slotted cover, rubber bands extending longitudinally within the box, resilient means for supporting said rubber bands in opposing contiguous relation, and a pair of abrasive strips lodged between the opposing surfaces of the rubber bands.

7. In a device of the character described, a box-like structure including a removable slotted cover, a pair of walls formed of resilient sheet metal spaced apart and extending longitudinally within the box, a pair of rubber bands in opposing contiguous relation with their ends flaring apart, and a pair of strips of abrasive material lodged between the opposing surfaces of the rubber bands.

In testimony whereof, I sign this specification in the presence of two witnesses.

CHARLES H. LAND, JR.
